CLAIM

The ornamental design for radius curve template, sub-
stantially as shown and described.

DESCRIPTION

FIG. 1 is a top plan view of a radius curve template
showing my new design.

FIG. 2 is a side elevational view thereof.

FIG. 3 is an end elevational view thereof.

FIG. 4 is a bottom plan view thereof.
FIG. 5 is an enlarged section view taken on line 5—5 of
FIG. 1.

FIG. 6 is a top plan view of a modified form of my new
design.

FIG. 7 is a side elevational view thereof.

FIG. 8 is an end elevational view thereof.

FIG. 9 is a bottom plan view thereof.

FIG. 10 is an enlarged section view taken on line 10—10
of FIG. 6.
